(57) **CLAIM**

The ornamental design for a vehicle speaker enclosure, as shown and described.

DESCRIPTION

FIG. 1 is a top view of a vehicle speaker enclosure showing my new design;

FIG. 2 is a front view thereof;

FIG. 3 is a bottom view thereof;

FIG. 4 is a left side view thereof;

FIG. 5 is a right side view thereof;

FIG. 6 is a bottom perspective view thereof; and,

FIG. 7 is a top perspective view thereof.

The broken lines depict portions of the vehicle speaker enclosure that form no part of the claimed design.
